UNITED STATES PATENT OFFICE

JOSEPH AVILA BOURBONNAIS, OF HOLYOKE, MASSACHUSETTS

AIR SUPPLY CONTROL MEANS FOR OIL BURNERS

Application filed September 23, 1930. Serial No. 483,785.

This invention relates to an improvement in vaporizing oil burners of the household type and is more particularly directed to the means for regulating and controlling the air supply for such burners. The present improvement is described and shown as applied to an oil burner of the type shown in my co-pending application Serial No. 447,582 of April 26, 1930.

10 Oil burners of this type are generally used by being mounted in the fire box space of an ordinary kitchen range to take the place of the usual coal fire therein. When so used, difficulties arise in connection with the distribution and supply of the proper amount 15 of air for efficient and smokeless combustion of the burner. The usual draft dampers of a household stove are ill adapted to the proper ventilation of an oil burner mounted in 20 the stove.

The common method of operation has been to keep the lower dampers of the stove as well as the chimney dampers wide open and thus give the oil burner at least all the air it 25 can use, allowing any surplus to pass up the chimney, the control of heat from the burner being regulated by the fuel supply. Such a method is unduly wasteful of fuel, frequently causes too large a current of unheated air to 30 pass from the fire chamber around the oven of the stove on the way to the chimney flue, making it difficult to heat the oven, and also permits drafts of unequal force to strike the 35 sides of the burner, causing uneven combustion. For best results in the operation of such a burner, the air should be supplied in the right quantity and with even diffusion to the bottom of the burner, and the outlet from the top of the burner to the chimney flue 40 should be free and unrestricted so as to carry off all products of combustion and prevent smoking or smell.

To this end, the present invention contemplates the provision of air supply control means closely adjacent the bottom of the burner which will break up the incoming draft into finely divided streams and the further provision of means for protecting the 45 sides of the burner and more particularly the

lower portions of the perforated cylinders from side drafts.

Further advantages and objects of the invention will become apparent from the following description taken in connection with 55 the accompanying drawing, in which:

Fig. 1 is a side view of the burner part in section shown as mounted in the fire chamber of a stove;

Fig. 2 is a plan view enlarged of the air 60 supply control means, one of the plates thereof being broken away to show the other plate beneath same;

Fig. 3 is a partial view similar to Fig. 1, showing a modified form of air supply control means.

Referring more particularly to Fig. 1 of the drawing, the fire chamber of an ordinary kitchen range is shown with walls 1 and 2 thereof, bottom 3, and top 4 in section. This 70 portion of the stove illustrated is that which usually contains the grate for the coal fire, which grate and fire brick have been removed and an oil burner of the type shown in my co-pending application shown therein.

The burner comprises a suitable adjustable stand 5 on the upper part of which is mounted the burner base 6 formed with fuel receiving grooves 7 and 8 and fuel vaporizing chamber 40. Surmounting the burner base 6 80 are the usual perforated cylindrical shells 9, 10, 11 and 12, and it will be understood that the spaces between the shells 9 and 10 and between 11 and 12 form the combustion chambers above their respective fuel grooves. 85 The fuel grooves 8 and 7 are also spaced apart in the usual way for allowing air to pass up between the same, as through the passage 13, so as to reach the space within shell 12 and between shells 10 and 11. Cover plates 14 and 15 are provided for the upper ends of the shells, as is customary. The fuel supply for the burner is indicated by the pipe 16 which leads into a passage extending upwardly through the stand 5 communicating with the fuel vaporizing chamber 40, and it will be understood also that the fuel receiving grooves 7 and 8 receive their fuel from the vaporizing chamber 40 through distributing conduits (not shown).

The ordinary kitchen range in which such burners are mounted is usually supplied through one wall thereof with a sliding damper such as indicated at 17 and perhaps also a door (not herein shown) at some lower portion of the fire box chamber. In operating an oil burner in such a stove it is customary to leave the ordinary stove damper or door open to give a sufficient supply of air for the burner. Experience has shown that when this is done too great a supply of air often reaches the burner and strikes one part of the burner in more abundance than another, so that the burner will not operate in a uniform manner.

To overcome this difficulty I have, therefore, provided an improved means for controlling the air supply for such a burner, which comprises in the present embodiment a pair of superposed perforated plates 18 and 19 mounted below the burner base, preferably on the upper portion of the stand 5. Both of the plates 18 and 19 are perforated as shown in Fig. 2, that is with a great number of relatively small apertures distributed in a substantially uniform manner throughout the area thereof. The plates 18 and 19 are made slidable upon one another, preferably by having lower plate 18 fixed and the upper plate 19 rotatable upon the stand 5 as a bearing. A handle 30 fixed to the upper plate 19 extends through a suitable opening 17' in the side of the stove to permit of its adjustment with respect to plate 18.

The upper plate 19 is also preferably perforated so that it never completely closes up all of the perforations in the lower plate 18 but provides that at all times there shall be some air passages through the two plates. For example: The lower plate 18 may have a series of concentric rings of equally spaced apertures 21, 22, 23, 24 and 25. The apertures in the rings 21, 23 and 25 may be of the same size while the apertures in ring 22 may be slightly larger and the apertures in ring 24 slightly larger still, or elongated as shown.

The upper plate 19 is of slightly smaller diameter than the plate 18 so that the outer ring 25 of apertures in plate 18 are not covered by plate 19. The upper plate 19 also has two concentric rings of elongated slots 26 which overlie the apertures 21 in plate 18, and elongated slots 27 which overlie the apertures 23 in plate 18 whereby the said apertures 21 and 23 of plate 18 are substantially uncovered in all relative adjustments of plate 19. The plate 19 also has two concentric rings of apertures 28 and 29, the apertures 28 overlying apertures 22, and the apertures 29 overlying apertures 24 of the plate 18, said apertures 28 and 22 being of the same size, and apertures 29 and 24 being of size and of such spacing that the adjustment of plate 19

may effect a complete closing or opening of the underlying apertures 22 and 24.

By the arrangement described, it will be clear that the plate 19 may be moved to restrict or enlarge some of the air passages through the combined plate structure, where as at all times there will be the provision of some air passages therethrough.

Mounted at the marginal portion of the lower plate 18 is an upwardly vertically extending imperforate shell 31 which extends part way up and around the perforated shells of the burner so as to protect and guard the lower portion of the same from the direct flow of air thereagainst.

Referring to Fig. 3 the stove structure and the burner here shown is the same as that previously described. In this modification the air control supply means comprises a lower plate 32 which extends entirely across from wall to wall of the stove compartment and is sealed and fastened around its entire margin to said walls as indicated by flange portions 33 and 34. This lower plate, therefore, entirely closes off the lower part of the fire box compartment from the upper part thereof wherein the burner base 6 is located. The lower plate 32, as shown at 35, may be perforated in the same manner as lower plate 18 as respects its area which is directly beneath the burner base 6. Above the lower fixed plate 32 is mounted the upper movable plate 19' which is constructed the same as plate 19, described in connection with Fig. 1. The operation of the structure in this modification is of course the same as that previously described, and has the additional advantage that the upper part of the burner is entirely surrounded by imperforate side walls 2, 3 and 4 of the stove so that no air can reach the same except that which passes upwardly through ventilating plates 19' and 32.

The advantage of this latter structure is that only heated air which passes through the burner is allowed to pass around the oven of the stove to the chimney flue. At the same time the chimney flue may be kept wide open for carrying off by a strong draft all the products of combustion.

It will be understood that in both constructions described, the adjustment of the upper plate 19 for giving the proper air supply to the burner is substantially fixed for each particular kitchen range with which the burner may be used. Different types of stoves will require perhaps a different adjustment of plate 19, but once the proper adjustment is obtained for the particular stove, it is left fixed and the control of the burner heat is obtained by regulation of the fuel supply in the customary manner.

What I claim is:

1. The combination with a vaporizing oil burner comprising a base with a plurality of fuel receiving troughs in air spaced relation

- and having vertically extended above the same spaced perforated shells to provide combustion chambers therebetween, of air supply control means for said burner comprising a 5 pair of superposed intersliding perforated plates mounted beneath said burner base, a portion of the perforations in the plates being arranged to provide adjustable ventilating apertures for the underside of the burner 10 and other of the perforations being arranged to continuously afford a non-adjustable minimum ventilation to the burner.
2. The combination with a vaporizing oil burner comprising a base with a plurality of 15 fuel receiving troughs in air spaced relation and having vertically extended above the same spaced perforated shells to provide combustion chambers therebetween, of air supply control means for said burner comprising a 20 pair of superposed intersliding perforated plates mounted beneath said burner base to provide adjustable ventilating apertures for the underside of the burner, said ventilating apertures being arranged in substantially 25 uniform spaced relation throughout said plates, the perforations of one of said plates being relatively large in number and small in size so as to supply air to said burner from below in finely divided streams.
3. The combination with a vaporizing oil burner comprising a base with a plurality of fuel receiving troughs in air spaced relation and having vertically extended above the same spaced perforated shells to provide combustion chambers therebetween, of air supply control means for said burner comprising a 35 pair of superposed intersliding perforated plates mounted beneath said burner base, a portion of the perforations in the plates being arranged to provide adjustable ventilating apertures for the underside of the burner and other of the perforations being arranged to continuously afford a non-adjustable minimum ventilation to the burner, and imperforate side walls extending vertically from said ventilating plates to surround the lower portion of said combustion chamber.
4. The combination with a vaporizing oil 50 burner comprising a base with a plurality of fuel receiving troughs in air spaced relation and having vertically extended above the same spaced perforated shells to provide combustion chambers therebetween, of air supply control means for said burner comprising a 55 pair of superposed intersliding perforated plates mounted beneath said burner base to provide adjustable ventilating apertures for the underside of the burner, said 60 ventilating apertures being arranged in substantially uniform spaced relation throughout said plates, the perforations of one of said plates being relatively large in number and small in size so as to supply air to said burner from below in finely divided streams.
- streams, and imperforate side walls extending vertically from said ventilating plates to surround the lower portion of said combustion chamber.
5. The combination with a vaporizing oil 70 burner comprising a base with a plurality of fuel receiving troughs in air spaced relation and having vertically extended above the same spaced perforated shells to provide combustion chambers therebetween, of air supply control means for said burner comprising a 75 pair of superposed intersliding perforated plates mounted beneath said burner base the perforations in the plates being arranged to provide both adjustable and non-adjustable ventilating apertures for the underside of the burner, and imperforate side walls joined to the margins of said ventilating plates and surrounding said burner.
6. The combination with a vaporizing oil 80 burner comprising a base with a plurality of fuel receiving troughs in air spaced relation and having vertically extended above the same spaced perforated shells to provide combustion chambers therebetween, of air supply control means for said burner comprising a 85 pair of superposed intersliding perforated plates mounted beneath said burner base to provide adjustable ventilating apertures for the underside of the burner, said 90 ventilating apertures being arranged in substantially uniform spaced relation throughout said plates, the perforations of one of said plates being relatively large in number and small in size so as to supply air to said 95 burner from below in finely divided streams, and imperforate sides walls joined to the margins of said ventilating plates and surrounding said burner.
7. The combination with a vaporizing oil 100 burner comprising a base with a plurality of fuel receiving troughs in air spaced relation and having, vertically spaced above the same, spaced perforated shells to provide combustion chambers therebetween, of air supply control means for said burner comprising a 105 pair of superposed intersliding perforated plates mounted beneath said burner base, to provide adjustable ventilating apertures for the under side of the burner, one of said plates being of larger area than the other, the larger plate being provided at its 110 extended uncovered portions with apertures affording a non-adjustable minimum ventilation for the burner.
- In testimony whereof I have affixed my signature.
